CABINET FOR A COMBINED MULTIPROGRAM PICTURE AND SOUND PROJECTION MACHINE OR SIMILAR ARTICLE

Henry A. Schwartz, Valley Stream, N.Y., assignor to
Color-Sonics, Inc., New York, N.Y.

Filed July 11, 1966, Ser. No. 3,013

Term of patent 14 years

(Cl. D61—1)

FIG. 1

FIG. 2

FIG. 3

FIG. 4

FIG. 1 is a front and right side perspective view of a cabinet for a combined multiprogram picture and sound projection machine or similar article, showing my new design. A portion of this figure is diagonally lined to indicate translucency. The loudspeaker grill shown fragmentarily is continuous within the boundaries indicated.

FIG. 2 is a top plan view;

FIG. 3 is a right side elevational view, the opposite side being substantially a mirror image thereof; and

FIG. 4 is a rear elevational view thereof.

I claim:

The ornamental design for a cabinet for a combined multiprogram picture and sound projection machine or similar article, substantially as shown and described.
